UNITED STATES PATENT OFFICE.

JOHN L. NILSON AND JOHN PRINCE, OF CHICAGO, ILLINOIS, ASSIGNORS TO UNIVERSAL PRODUCTS COMPANY, OF MEMPHIS, TENNESSEE, A CORPORATION.

LIQUID-LEVEL GAUGE.

Application filed November 1, 1920. Serial No. 421,149.

To all whom it may concern:

Be it known that we, JOHN L. NILSON and JOHN PRINCE, citizens of the United States, residing at Chicago, in the county of Cook and State of Illinois, having invented certain new and useful Improvements in Liquid-Level Gauges, of which the following is a specification.

Our invention relates to gauges showing the depth of liquid in a liquid-fuel tank for automobiles and the like, and has particular reference to their combination with the cap for the inlet-opening into the tank. The object of the present invention is to simplify, lower the construction cost and make more conveniently operable these combination caps and gauges, and with this general object in view our invention consists of the novel combination and arrangement of parts hereinafter described in detail, illustrated in the accompanying drawing, and more particularly pointed out in the appended claims.

In the drawing—

25 Figure 1 is a perspective view of a broken away section of automobile tank and a perspective view of an embodiment of our invention applied thereto.

Figure 2 is an edge elevation on an enlarged scale of the gauge removed from the tank together with the cap to which it is attached shown in section and a side view of the graduated gauge-bar or elastic strip broken away at its ends.

35 Figure 3 is a plan view of an open packing box or case, showing the adaptability of our improvement for storing or transportation purposes.

In the several views 2 represents a gasoline tank provided with the usual threaded flange 3 for the inlet opening 4 to be normally closed by the usual cap 5 having threads 5' to be engaged with the threads of the opening rim 3. For the purposes of the 45 present improvement these parts may be varied in numerous ways.

In the present invention the cap 5 is relieved of the more or less expensive and complicated adjuncts or attachments here-

50 tofore provided for this class of combinations, and has merely a pair of oppositely projecting lugs 6 and 7 which may be either separately attached or cast integral with the cap. The lug or boss 6 is upwardly projected near the periphery of the cap and is

a slide-bearing lug with a slot 8 therethrough and through the cap 5 that is slidably engaged by a gauge-bar 9 having graduations 10 thereon and preferably made of elastic material so that it will restore itself to normal, or straight, form when bent, accidentally or otherwise, as for packing purposes, as shown in Figure 3. The downwardly projecting lug 7 is an elevating rest or foot of substantially the same height above the tank top as its flange 3, and its purpose is to support that portion of the cap which is opposite to that which rests on the flange 3, on the same level when the cap is in its open position as in Figure 1, and to preserve the normal vertical position of the slot 8 to prevent binding therein of the gauge-bar 9. On the lower end of the latter is the usual float 11, which may be of any desired form or design. The numeral 12 indicates the liquid level in the tank. The upper end of the gauge-strip 9 is bent to form a hook-formed clip or clamp 14 with an outturned lip 15 to be engaged with a recess 16 in the side of the boss 6 when the cap is closing the opening 4 and the graduated gauge-strip is not in use, thereby holding the latter out of the way. The cap 5 is as free of the tank as any ordinary plain cap in its Figure 1 position. The gauge bar or strip may be of any other suitable cross-sectional form than that shown in the present illustration of our invention. The cap 5 is shown with a top flange 17 to provide a protecting recess for the clip 14 or to prevent an undesirable projection thereof above the cap. The gauge-bar may be conveniently made of clock-spring material and will then not be damaged by accidental bendings or contacts with the gauge projecting above the tank as when the latter is full or nearly full. The float may be attached to the lower end of the gauge-bar by any simple friction engagement so that the parts may be readily separated and the gauge slipped out of its bearing if desired, but such details may be varied in numerous ways and in a very simple manner.

By reference to Figure 1 it will be noted that the off center arrangement of the gauge-bar 9, or its emplacement near the edge of the cap 5, permits the latter to be substantially removed from the opening 4. In gauge bars placed through the center of

the cap the opening 4 cannot be cleared without removing the cap indicator and float. The present improvement is designed to operate while the refilling of the tank takes place like permanently attached gauges instead of being merely a measuring bar attached to the cap to insure its presence when needed and serving merely as a plain rule or gauge stick.

10 We claim as our invention—

1. A liquid level gauge for tanks comprising a cap adapted to be detachably fitted to the usual inlet opening of a storage tank, said cap having a guide slot therethrough, an ullage rod slidably fitting in said guide slot and having graduations thereon, visible above the cap when in position, a float on the lower end of said rod for supporting the lower end of the same at the surface level of the liquid in the tank, and means for releasably holding the upper end of said rod to the cap when the rod is drawn down through the cap, said rod being sufficiently resilient whereby the rod is adapted 20 to be bent over at its lower end for bringing the float against the cap and folding the de-

vice compactly for storage and shipment and easy handling.

2. A liquid level gauge for tanks comprising, a cap adapted to be detachably mounted in the filling opening of a storage tank and having a guide slot therethrough and spaced from the vertical axis thereof, an ullage rod slidably fitting through said guide slot, a float on the lower end of the rod for raising and lowering the same with the rise and fall of the surface level of the contents in the tank, said cap being adapted to be detached from the tank and to be swung to one side in partial overlapping relation to the filling opening of the tank and with the rod and the float projecting down into the tank, said cap having a depending lug at its side remote from the rod to support the cap horizontally on the edge of the flange surrounding the tank opening and permit the free vertical movement of the rod when filling the tank.

In testimony whereof we have hereunto signed our names.

JOHN L. NILSON.
JOHN PRINCE.
